UNITED STATES PATENT OFFICE.

WILLIAM BUTTLER, OF REDKEY, INDIANA.

DESIGN FOR SHEET-GLASS.

SPECIFICATION forming part of Design No. 33,603, dated November 20, 1900.

Application filed June 1, 1900. Serial No. 18,779. Term of patent 14 years.

To all whom it may concern:

Be it known that I, WILLIAM BUTTLER, of Redkey, in the county of Jay and State of Indiana, have invented a new and original Design for Sheet-Glass, of which the following is a full, clear, and exact description, reference being had to the accompanying drawing, which shows in plan view a sheet of glass embodying my design.

In the drawing the sheet of glass 2 is shown as having a series of figures composed of rays 3, emanating from points 3' and surrounded

by a border composed of a band 4 of irregular contour.

I claim—

The design for sheet-glass, substantially as herein shown and described.

In testimony whereof I have hereunto set my hand.

WILLIAM BUTTLER.
